UNITED STATES PATENT OFFICE.

WILLIAM HAEHNEL, OF NEW YORK, N. Y., ASSIGNOR TO PALM & FECHTELER, OF SAME PLACE.

DESIGN FOR ORNAMENTATION OF SEWING-MACHINES.

SPECIFICATION forming part of Design No. 15,005, dated May 20, 1884.

Application filed March 28, 1884. Term of patent 7 years.

To all whom it may concern:

Be it known that I, WILLIAM HAEHNEL, of New York, N. Y., have invented and produced a new and original Design for Ornamentation of 5 Sewing-Machines, of which the following is a specification.

This design relates to the ornamentation of sewing-machines and other articles; and it consists in the novel grouping and configuration 10 of figures, hereinafter more fully described.

The accompanying illustrations show in Figures 1 and 2 opposite views of a sewing-machine plate and arm having thereon my new design. Figs. 3 and 4 are full-size detail views 15 of the ornamentation at the sides of the cloth-plate. Fig. 5 is a full-size detail view of the ornamentation in the center of the cloth-plate. Fig. 6 is a full-size detail view of the ornamentation at the front portion of the cloth-plate. Fig. 7 is a full-size detail view of the ornamentation on the side of the sewing-machine arm. Fig. 8 is a full-size detail view of 20 the ornamentation on the front of the sewing-machine arm. Fig. 9 is the ornamentation on 25 the side of the needle-carrying portion of the sewing-machine arm. Fig. 10 is the ornamentation on the side of the post sustaining the sewing-machine arm.

The figures A, which ornament the top of 30 the cloth-plate near its sides, consist each of a long curved spray set with leaves and blossoms, like those of the lily of the valley, and also small pointed leaves, and bearing also clusters of buds set close on stems, similar to 35 the hollyhock.

Figure B, which ornaments the center of the cloth-plate, consists of a landscape picture showing a country house with trees and lawn surrounding it, a river and bridge, and mountains in the background, the picture being enclosed by an oval frame and tendrils bearing small pointed leaves and buds and blossoms, similar to those already described.

Figure C, which ornaments the front portion 45 of the cloth-plate, consists of two curved sprays crossing each other and bearing large and small leaves and blossoms, similar to those already described, and also clusters of hollyhock-like buds.

Figure D, which ornaments the sides of the 50 sewing-machine arm, consists of a tendril bear-

ing leaves and blossoms, similar to those already described, and also the clusters of buds, and twining around the inscription "New Home," or other inscription, all placed against 55 the side of the sewing-machine arm.

Figure E, which ornaments the front of the sewing-machine arm, consists of several curved sprays running alongside of each other and bearing large and small leaves, blossoms, and 60 buds, similar to those already described.

Figure F, which ornaments both sides of the needle-carrying portion of the sewing-machine arm, consists of a curved spray bearing leaves and clusters of buds, similar to those already 65 described.

Figure G, which ornaments both sides of the post sustaining the sewing-machine arm, consists of a long and a short curved spray running alongside of each other and bearing large 70 and small leaves, blossoms, and clusters of buds, similar to those already described.

I claim—

1. The design for the ornamentation of sewing-machines, consisting of the figure A, substantially as shown.

2. The design for the ornamentation of sewing-machines, consisting of the figure B, substantially as shown.

3. The design for the ornamentation of sewing-machines, consisting of the figure C, substantially as shown.

4. The design for the ornamentation of sewing-machines, consisting of the figure D, substantially as shown.

5. The design for the ornamentation of sewing-machines, consisting of the figure E, substantially as shown.

6. The design for the ornamentation of sewing-machines, consisting of the figure F, substantially as shown.

7. The design for the ornamentation of sewing-machines, consisting of the figure G, substantially as shown.

8. The design for the ornamentation of sewing-machines, consisting of the figures A B C D E F G.

WILLIAM HAEHNEL.

Witnesses:

WILLY G. E. SCHULTZ,
GUSTAV SCHNEPPÉ.
